No. 734,042.

PATENTED JULY 21, 1903.

A. B. BULLOCK.

SWITCH STAND.

APPLICATION FILED MAY 11, 1903.

NO MODEL.

UNITED STATES PATENT OFFICE.

ALVA B. BULLOCH, OF BIRMINGHAM, ALABAMA, ASSIGNOR OF ONE-HALF
TO T. J. BURTON, OF EDWARDSVILLE, ALABAMA.

SWITCH-STAND.

SPECIFICATION forming part of Letters Patent No. 734,042, dated July 21, 1903.

Application filed May 11, 1903. Serial No. 156,650. (No model.)

To all whom it may concern:

Be it known that I, ALVA B. BULLOCH, a citizen of the United States, residing at Birmingham, in the county of Jefferson and State of Alabama, have invented certain new and useful Improvements in Switch-Stands; and I do declare the following to be a full, clear, and exact description of the invention, such as will enable others skilled in the art to which it appertains to make and use the same.

This invention relates to certain new and useful improvements in switch stands and throws for railroad-switches.

The object of the invention is to provide a device of this character which is simple in construction, durable in use, efficient in operation, and comparatively inexpensive of production.

With this and other objects in view the invention consists of certain novel features of construction, combination, and arrangement of parts, as will be more fully described, and particularly pointed out in the appended claims.

In the drawings, Figure 1 is a perspective view of my improved switch-throw. Fig. 2 is a bottom plan view of the same. Fig. 3 is a vertical longitudinal sectional view. Fig. 4 is a detail sectional view through a portion of one end of the casing, showing the guide for the locking-pin.

Referring to the drawings by numerals, 1 denotes a cast-metal housing or frame which comprises the semicylindrical portion 2 and the horizontal base-flanges 3, by means of which the casting is secured upon a suitable foundation adjacent to the railroad-track. Extending longitudinally through and slidably journaled in the semicylindrical portion 30 of the housing is a shaft 4, one end of which is swiveled or loosely connected to the rod 5, which moves the switch-point. 6 denotes an operating-lever one end of which is fixedly secured to the shaft 4 within the housing, and the free end thereof is provided with the weight 7. Said operating-lever projects through and travels in an angularly or diagonally arranged slot 8, formed in the top of the semicylindrical portion of the housing or frame. It will be seen that by throwing the operating-lever to either side of the housing

the shaft 4 will be partially rotated and at the same time moved longitudinally to operate the switch-point through the connecting-rod 5.

In order to hold or lock the parts in either position, the shaft is provided with the openings or apertures 9, which are adapted to be engaged by the vertically-sliding lock-pin 10. Said pin slides in suitable guides 10' upon one end of the housing and projects through the top of the same. Its upper end is formed with an eye 11, which is adapted to register or aline with an eye 12, formed upon the top of the housing, so that the bail of a padlock 65 or other fastening device may be passed through said eyes to lock the pin in engagement with the shaft. In order to actuate the locking-pin 10, a foot-lever 11' is pivoted between the integral lugs 12, formed upon the 70 end of the housing. Said foot-lever has its inner end projecting through an opening in the end of the housing and is connected by a link or rod 13 to a lug formed upon the lock-pin 10. By depressing the foot-lever 11 75 it will be seen that link 13 will elevate the pin 10 and free it from engagement with the openings 9 in the shaft 4.

14 denotes a vertical target-shaft which is journaled in the integral bearing 15 upon the 80 housing. Collars 17, secured to said shaft upon each side of the bearings, prevent the vertical movement of the shaft. Upon the upper end of this vertical shaft is a sleeve 18, which carries the target-wings 19. A bolt 18^a, 85 passing through said shaft, sleeve, and the target-wings 19, secures said parts together. In the upper end of this sleeve is a plug or bar 18^b, having a beveled upper end to fit in the bottom of the switch-lamp. Said plug is secured in the sleeve by the bolt 18^c, which also passes through the red and white target-wings 19. The lower end of the vertical target-shaft 14 within the housing is provided with a crank arm or portion 21, the end of which 95 is provided with a bolt or pin 22, which projects through a slot 23, formed in an arm 24, projecting from a loose sleeve 25 upon the shaft 4. Said sleeve 25 can turn upon the shaft; but the set-screws 26 upon each side 100 thereof prevent any longitudinal or sliding movement upon the shaft. The slotted arm

24 is held in engagement with the bolt or pin 22 by the nut or head 27 upon its end.

The operation of the device is as follows: The operator presses his foot down upon the 5 outer end of the lever 11', which will raise the locking-pin 10, as previously explained, and unlock the shaft 4. The weighted operating-lever 6 is then thrown from one side of the housing to the other, and in this movement it will travel the diagonal or angular slot 8, and thereby impart a longitudinal sliding movement to the shaft 4 as well as a rotary movement. The longitudinal movement, as explained, will operate the switch- 10 point through the instrumentality of the connecting-rod 5, and the same movement of the shaft 4 will rotate the crank end 21 of the target-shaft by means of the slotted arm 24, and thereby operate the target. When the 15 foot-lever is released, it will permit the locking-pin 10 to drop into either of the openings 9 in the shaft 4 in order to lock the same.

From the foregoing description, taken in connection with the accompanying drawings, 20 the construction and operation of the invention will be readily understood without requiring a more extended explanation.

Various changes in the form, proportion, and the minor details of construction may 25 be resorted to without departing from the principle or sacrificing any of the advantages of this invention.

Having thus described my invention, what I claim, and desire to secure by Letters Patent, is—

1. In a device of the character described, the combination of a frame or housing formed with an angularly-arranged slot, a shaft journaled in said frame, an operating-lever secured to said shaft and operating in said slot, a target-shaft journaled in said frame and formed with a crank end, and a connection between the first-mentioned shaft and

said crank whereby the target is operated upon the movement of the first-mentioned 45 shaft, substantially as described.

2. In a device of the character described, the combination of a frame or housing formed with an angularly-arranged slot, a shaft journaled in said frame and formed with locking- 50 apertures, an operating-lever carried by said shaft and operating in said slot, a locking-pin to coact with said locking-apertures, a lever and connection between said lever and pin for operating said pin, substantially as 55 described.

3. A switch-stand comprising a frame or housing formed with a diagonal slot, a shaft journaled in said frame, an operating-lever secured to said shaft and projecting through 60 said slot, means for locking said shaft against movement, a loose sleeve upon said shaft formed with a slotted arm, a target-shaft journaled in bearings in said frame, a crank-arm upon said shaft and coacting with said 65 slotted arm, and an adjustable sleeve upon the target-shaft carrying target-wings, substantially as described.

4. A switch-stand comprising a frame or housing formed with a diagonal slot, a shaft 70 journaled in said frame and provided with locking-apertures, an operating-lever secured to said shaft and projecting through said slot, a target, connections between said target and shaft for operating the same, a sliding locking-pin coacting with said locking-apertures, a lever pivoted to said frame, and a link between said lever and pin, substantially as described.

In testimony whereof I have hereunto set 80 my hand in presence of two subscribing witnesses.

ALVA B. BULLOCH.
